(57) **CLAIM**

We claim the ornamental design for a guitar stand, as shown and described.

DESCRIPTION

FIG. 1 is a side perspective view of a guitar stand showing our new design;

FIG. 2 is another side perspective view of the guitar stand of FIG. 1;

FIG. 3 is a top perspective view of the guitar stand of FIG. 1;

FIG. 4 is a front perspective view of the guitar stand of FIG. 1;

FIG. 5 is a side perspective view of the guitar stand of FIG. 1, showing a guitar in phantom; and,

FIG. 6 is a front perspective view of the guitar stand of FIG. 1, showing a guitar in phantom.

The broken lines showing in FIGS. 5 and 6 are for the purposes of illustrating the environment of the article only and form no part of the claimed design.
